DEVELOPMENT REEL

Le Roi E. Hutchings, Tonawanda, N. Y., assignor
to Remington Rand Inc., Buffalo, N. Y.

Application February 13, 1930. Serial No. 428,193

5 Claims. (Cl. 242—55)

This invention relates to winding and reeling devices, and it has particular reference to a device adapted to support a photographic film or paper during the development thereof.

5 The invention contemplates the provision of a device in which the several wraps of film or paper are spaced in order to permit of the access thereto of the developing and washing solutions, and in which the spacing members are readily positioned and removed, as the film is either wound or unwound from the reel. The several objects and advantages of the invention will be made more apparent from a perusal of the following description of a specific embodiment thereof, 10 with reference to the accompanying drawings wherein:

Fig. 1 is a side elevational view of the winding and reeling device, the film or paper being schematically indicated thereon;

20 Fig. 2 is an end elevational view of the assembly;

Fig. 3 is a fragmentary side elevational view of the hub portion of the reel, the view being taken between the spokes and drawn on an enlarged 25 scale;

Fig. 4 is a fragmentary plan view of the inner face of a spoke, showing some of the spacing members in cross section;

Fig. 5 is a cross-sectional view taken along the 30 line 5—5 of Fig. 3;

Fig. 6 is a view in perspective of a spacing member; and

Fig. 7 is a longitudinal cross-sectional view of a winding spool.

35 As shown in Figs. 1 and 2, the assembled device comprises a base plate 10 having positioned therein a vertically disposed standard 11 provided at about its mid-portion with a horizontally extending stub shaft or axle 12 adapted to rotatably support a reel, designated generally by the reference numeral 13. The upper end of the standard 11 terminates in a horizontally disposed bearing 14 adapted to receive the trunnion or shaft 15 of a spool 16. One end of the trunnion or shaft 15, projecting through the bearing 14, is adapted to receive a crank or handle 17, by means of which the spool 16 may be rotated in either direction, either to wind or unwind a film on the spool from the reel 13.

50 As further illustrated in Fig. 7, the spool 16 comprises a hollow cylindrical portion 18 to the ends of which are affixed face plates 19 and 21 of greater diameter. The plate 19 is secured by means of a collar member 22, adapted to be positioned on the trunnion 15 and to bear against the bearing 14, which collar is formed with a radially extending finger 23 provided with a laterally extending detent 24 which passes through an aperture formed in the plate 19 and into a recess 55 formed in the end of the wall of the cylinder 18.

A set screw may be employed to interlock the collar 22 and the shaft 15, and, as it will be readily observed, when the parts are assembled as shown, the shaft, end plate, and cylinder are all fixedly interconnected. The end of the shaft 65 15 adjacent the opposite end of the cylinder 18 is screw-threaded, as indicated by the reference numeral 26, and projects through a centrally disposed aperture formed in the end plate 21, to receive a knurled nut which, when tightened, retains 70 the entire assembly in place. A fiber washer 28 may be interposed between the nut 27 and the face of the end plate 21.

It is contemplated that the spool 16 shall be employed to receive the undeveloped film or paper in the photographing machine, and the construction accordingly is such that the spool may be readily transferred to and assembled upon the standard 11 prefatory to winding the film on the reel 13. The spool 16 is also adapted to receive the developed film from the reel by simply reversing the direction of rotation by turning the handle 17.

The reel 13 consists of a hub member formed with a pair of substantially square plates 31 which are spaced and interconnected by means of cross bars 32 extending between their corners. Secured to the inner faces of the plates 31, and extending outwardly along both diagonals thereof, are spokes 33, so constructed as to receive detachable 90 spacing members 34, (see Fig. 6), upon which the film is wound.

As shown in Figs. 3, 4 and 5, each plate 31 is stamped or otherwise shaped to form a marginal 95 inwardly projecting flange 35, and is drawn out at the corners so that the flange 35 may lie snugly on either side of the spokes 33. The cross bars 32 are likewise formed with marginal flanges, which are cut away at the ends of the bars, to provide projecting fingers which embrace the 100 spokes 33, and fit into correspondingly cut away portions of the flanges 35, as indicated by the numeral 36 in Figs. 2 and 5. The spokes 33 are provided with doubly bent flanges 37 projecting first inwardly parallel to the axis of the reel, and then toward each other, to form pockets 38. The spokes for each plate 31 project under the recessed portions of the cross bars 32, along the diagonals of the plate 31, abutting adjacent the center 110 thereof, and are there secured by angle members 39. All of the parts may be formed by simple drawing and pressing operations, when the parts are made of resistant sheet metal, as is desirable to prevent corrosion, and may be secured to each 115 other by spot welding. As illustrated, the plates 31 are apertured intermediate the diagonal portions, and the plates and spokes are provided with a plurality of spaced apertures 41, serving 120 to permit the penetration of developing liquid to

the film, or drainage therefrom, as the case might be.

It will be understood that, when the parts are assembled, there is provided a reel in which the 5 cross bars 32 define the hub upon which the film or strip may be wound and which is retained on the hub by means of the spokes 33. In order to space each wrapping of film, a number of spacers 34 are provided, which are of semi-cylindrical form with squared and flanged ends 42. The flanges 42 are of such dimensions that they fit within the pockets 38 formed on the spokes 32 and between an opposed pair of spokes, so that they may be assembled with the reel by 10 dropping in from the ends of the spokes, but can not thereafter be displaced by pulling endwise or by twisting or tilting. When a pair of opposed spokes are pointed upwardly away from the hub, a spacer placed between them will slide down, 15 under the influence of gravity, until it meets some obstruction, such as the hub or cross bar, or another spacer. When the spokes are pointed downwardly, the spacer will slide down, and fall out, unless it is retained by means of a 20 wrap of film.

In order to mount the reel for winding or unwinding a film, there is provided at the center point of each plate an aperture 43 adapted to receive the axle 12. As shown in Fig. 2, the axle 30 may be of reduced diameter and formed of a section 45 which is adapted to be threaded into the main portion 12, to provide a stop shoulder limiting the inward movement of the reel.

In operation, a spool 16 having a film or 35 other length of material wound thereon is positioned on the standard 11, and an empty reel 13 is positioned on the axle 12. The outer end of the film is then secured to the hub of the reel, by a clip or other suitable means, and the film is then 40 unwound from the spool and on to the reel, by rotating the reel, employing the spokes 33 as hand holds. As shown in Fig. 1, the winding rotation is clockwise, and as each pair of spokes come up into the second quadrant position, a spacer 34 45 is dropped into the aligned pockets 38. As the pair of spokes reach the first quadrant position, the film is applied thereto, and over the cylindrical face of the spacer, holding it in position as the same pair of spokes pass through the fourth 50 and third quadrant positions. This procedure is continued until all of the film has been wound on the reel, when the end is made fast, and the reel and film are then removed for developing or such other treatment as is indicated. In case 55 the reel is immersed in a developing or washing solution, it will be seen that the apertures 41 permit the ready access of the liquid to the spaced wraps of film, or drainage therefrom. After the film has been treated, the reel is again 60 placed on the axle 12, and unwound back onto the spool 12, by means of the handle 17. Counter-clockwise rotation of the reel is now effected, so that, as each pair of spokes reach the third quadrant position, the spacers 34 are no longer 65 restrained from sliding downwardly and falling away.

It will be understood, therefore, that the invention provides a simple and effective way of winding films or the like on a reel including means for 70 spacing the successive wraps of the film in a positive manner. I am aware that prior to this invention, it has been proposed to space such wrapping, but I regard it as novel with me to space the wraps by means which may be so readily applied 75 during winding, and which automatically remove

themselves during the unwinding operation. It will accordingly be understood that I desire the foregoing description regarded as illustrative of the principles of the invention, as set forth in the following claims.

80

I claim:—

1. A reel comprising a hub member, pairs of radially aligned spokes extending outwardly therefrom, each of said spokes being formed with marginal flanges forming open pockets on the inner sides thereof, and spacing members adapted to be positioned between the pockets by a sliding movement along the spokes from the ends thereof, said spacing members being formed with hollow squared ends adapted to be retained in the pockets, and apertures formed in the spokes to permit of access of liquid through the hollow ends between the spacers.

85

2. A reel comprising a pair of opposed polygonal plates each provided with a central bearing portion, a plurality of radial spokes secured on each plate and arranged to extend from the bearing portion through the corners thereof, cross bars connecting the spokes on opposed plates adjacent the corners thereof, said cross bars securing the 100 plates in spaced parallel relation with the bearing portions in coaxial relation and with the sides of the plates in aligned relation, inwardly extending pockets on each spoke, and spacing members slidably positioned in the pockets between the spokes.

95

3. A reel comprising a hub member, spaced pairs of radially aligned spokes extending from the hub member, said spokes being formed with grooves in their inner faces, spacing members slidably positioned in the grooves between opposed spokes, said spacing members being formed to provide a relatively thin arcuate central portion and squared end portions, said end portions abutting end portions of adjacent spacing members to space the central portions relative to 110 each other and also to retain the spacing members against axial movement with their central portions in predetermined relation to each other.

105

4. A spacing member for a reel formed of a piece of sheet metal comprising a film supporting central section of curved transverse section and end sections having laterally extending parallel side flanges, the transverse dimension of said central section being substantially greater than said end sections, whereby the ends of said side flanges will 120 engage the opposite sides of the end sections of an adjacent spacing member for supporting the central section thereof in predetermined spaced relation to the central section of said adjacent spacing member when arranged in superimposed 125 relation.

110

5. In combination with a reel having spoke members and channel shaped slide portions formed on said spoke members, a plurality of film spacing members each comprising a film supporting central section and end sections having laterally extending parallel side flanges, the transverse dimension of said central section being substantially greater than said end sections, whereby the said end sections cooperate with said channel shaped slide portions to hold said spacing members from turning movements and whereby the ends of said side flanges engage the opposite sides of the end sections of adjacent spacing members for supporting the central sections thereof in predetermined spaced relation to the central sections of said adjacent spacing members when assembled with said reel.
